UNITED STATES PATENT OFFICE.

ALBERT ROTH, OF CRIMMITSCHAU, GERMANY.

REDUCING-VALVE.

SPECIFICATION forming part of Letters Patent No. 761,106, dated May 31, 1904.

Application filed September 18, 1903. Serial No. 173,679. (No model.)

To all whom it may concern:

Be it known that I, ALBERT ROTH, a subject of the German Emperor, residing at 44 Beyerstrasse, Crimmitschau, Saxony, Germany, have invented certain new and useful Improvements in Reducing-Valves; and I do hereby declare the following to be a full, clear, and exact description of the invention, such as will enable others skilled in the art to which it applies to make and use the same.

This invention relates to a reducing-valve by means of which the steam taken from a high-pressure steam-pipe can be reduced to the lowest conceivable point of pressure. The intended purpose is mainly effected by placing the low-pressure side of the apparatus in communication with an expansion-body such as is already employed in many forms in connection with devices for reducing steam-pressure, so that only when a certain pressure is reached in the low-pressure chamber is it possible for the steam to reach the expansion-body, which then in the usual manner in consequence of its expansion causes the steam-inlet valve to close.

The possibility above mentioned of a flow of steam to the expansion-body when a certain internal pressure is produced in the low-pressure side of the apparatus is insured by the introduction between the low-pressure side and the expansion-body of a resistance which the steam must overcome. This resistance may be in the form of a valve of the safety-valve type loaded with a spring, a weight, or a lever.

In the accompanying drawings that form of the invention is illustrated in which a spring-loaded safety-valve is introduced as a resistance.

Figure 1 is a general view of the steam-pressure-reducing device; Fig. 2, a plan of the apparatus.

The arrangement is as follows: The spindle *a* of the inlet-valve *v* is carried through a stuffing-box *b*, situated opposite to the said valve and connected outside the valve-chamber with the angle-lever *d*, which pivots around the pin *c*. This connection may be effected by means of a screw-bolt; but it is sufficient if the angle-lever *d* presses against the

valve-spindle. The short arm of the angle-lever *d* lies against the end of an expansion-body *k*, the interior of which is in communication with the low-pressure side of the valve-chamber through the circulation-pipe *p* and the resistance-valve arranged on the valve-chamber. The valve-cone *f* of the resistance-valve is loaded with a spring, so that it is only when a certain pressure prevails on the low-pressure side that the cone is raised and the passage for the steam to the expansion-body *k* thus opened. The load on the cone *f* in the resistance-valve is varied or adjusted by turning the handle *h*, which raises or lowers a screw-threaded guide-sleeve, and thus places the spring under a higher or lower degree of tension.

In the drawings the expansion-body is shown as a pipe which is heated from within. In order that the sides of the pipe may be quickly heated with as little steam as possible, a body *g* which is a bad conductor of heat is arranged in the tube, leaving but a very small internal space. As regards the action of the apparatus it is immaterial so far as concerns the expansion-body whether the inner or the outer surface of such body be placed in communication with the low-pressure side of the valve-body or whether the expansion-body be made solid or in the form of a pipe or whether the solid body be replaced by a body filled with a suitable fluid, in which case the expansive capacity of the particular fluid would form the actuating moment.

The action of the apparatus is as follows: If, for example, a low-pressure steam-heating device be supplied with steam, the high-pressure steam through its own pressure and the velocity at which it flows in will keep the valve *v* open until the expansion-body *k* is heated. This heating is effected in the following manner: When the pipe to be furnished with steam has been duly filled, the pressure of steam will rise gradually on the low-pressure side until it has reached the point at which the cone of the resistance-valve is raised. In consequence of this opening of the resistance-valve a passage is opened for the steam to the circulation-pipe *p*, which conveys the steam to the expansion-body, whereby this body is heated. Being thus heated, the expansion-

body expands in the direction of its length and presses the angle-lever d against the movable valve-spindle a , which is moved inward—that is, in the direction of the valve-seat. The 5 expansion of the body k is regulated in relation to the angle-lever d , so that by the expansion of the body k the valve-spindle a is forced toward its valve-seat, and thereby the steam coming from the high-pressure pipe 10 throttled and, if necessary, entirely cut off. Hereby the steam-pressure in the low-pressure side of the apparatus is so far reduced that the resistance-valve no longer allows steam to reach the expansion-body k , and the 15 expansion-body cools again and contracts. In consequence of this the angle-lever allows the valve-spindle play for the opening of the valve, so that high-pressure steam can flow afresh into the low-pressure heating device. 20 The lever connection between the expansion-body k and the valve-spindle a may be replaced by tooth-wheel gearing and the object even be effected without either by the employment of a corresponding long and correspondingly-suitable expansion-body directly 25 connected with the spindle or actually forming the spindle.

What I claim, and desire to secure by Letters Patent, is—

30 1. A reducing-valve comprising a valve-chamber with inlet and outlet openings, a valve seated in the chamber and dividing it into high and low pressure compartments, an expansion-body capable of being expanded by the steam

admitted to it from the low-pressure compartment and adapted to force the reducing-valve toward its seat, a conduit arranged to convey the steam to the expansion-body, and a resistance situated in the area of the low-pressure compartment and interposed between the 35 conduit and said compartment so that the steam can only reach the expansion-body after a fixed pressure controlled by the resistance is reached in the low-pressure compartment. 40 2. A reducing-valve comprising a valve-chamber with inlet and outlet openings, a valve seated in the chamber and dividing it into high and low pressure compartments, an expansion-body capable of being expanded by the steam admitted to it from the low-pressure compartment and adapted to force the reducing-valve toward its seat, a conduit arranged to convey the steam to the expansion-body, a resistance 45 situated in the area of the low-pressure compartment and interposed between the conduit and said compartment so that the steam can only reach the expansion-body after a fixed pressure controlled by the resistance is reached in the low-pressure compartment; and means 50 for adjusting said resistance, to varying pressures, from outside the valve-chamber. 55

In testimony whereof I have affixed my signature in presence of two witnesses.

ALBERT ROTH.
